(57) **CLAIM**

The ornamental design for a sensorial activity toy as shown and described.

DESCRIPTION

FIG. 1 is a top-left perspective view of the sensorial activity toy of the present invention; FIG. 2 is a bottom-right perspective view of the invention shown in FIG. 1;

FIG. 3 is a front elevation view of the invention shown in FIG. 1; and,

FIG. 4 is a rear elevation view of the invention shown in FIG. 1.

The drawings illustrate a sensorial activity toy having a plurality of protrusions extending from a board portion, which protrusions form channels there between. Contour lines are included in the various views of FIGS. 1 through 4 to depict surface curvature, flatness and other shapes. Portions illustrated in broken-lines form no part of the claimed design.
